MICROPHONE

Louis R. Burroughs, Buchanan, Mich., assignor to Electro-Voice, Incorporated, Buchanan, Mich., a corporation of Indiana

Application September 20, 1957, Serial No. 47,798

Term of patent 14 years

(Cl. D26—14)

Figure 1 is a side elevational view of a microphone, showing my new design, the opposite side being substantially a mirror image thereof;

Figure 2 is a front elevational view;

Figure 3 is a top plan view;

Figure 5 is a front elevational view thereof from a somewhat different angle than in Figure 2.

The dominant features of my new design are shown in solid lines in the drawing.

I claim:

The ornamental design for a microphone, as shown and described.
